UNITED STATES PATENT OFFICE.

LOUIS LANE, OF HABANA, CUBA.

SASH-GEAR BALANCE.

Application filed August 30, 1922. Serial No. 585,268.

To all whom it may concern:

Be it known that I, LOUIS LANE, a citizen of the United States of America, and a resident of Habana, Cuba, have invented a new and Improved Sash-Gear Balance, of which the following is a description.

My invention relates to balanced sliding sashes having gear connections therebetween so that a movement of one sash will impart 10 a reverse movement to the other.

With sashes balanced in the ordinary manner by weights, cords and pulleys, any irregularity of contact between a sash and guideway on one side as compared to the 15 other side has a tendency to permit the freer side to advance, thus throwing the sash askew or out of its proper perpendicular plane and thereby producing a binding at the retarding corner, the result being a 20 sticking of the sash or jamming of the sash in the guideway. My invention provides a balance gearing so arranged that when properly adjusted it will not be possible for one sash side to advance ahead and the consequent binding and sticking of the sash is 25 thereby prevented.

The nature of the invention and its distinguishing features and characteristics will clearly appear as the description proceeds.

Reference is to be had to the accompanying drawings forming a part of this specification, it being understood that the drawings are merely illustrative of some examples of the invention.

Figure 1 is a partly sectional elevation, the view being indicated by the line 1—1, Figure 2;

Figure 2 is a horizontal section on the line 2—2, Figure 1;

Figure 3 is a detail in vertical section as indicated by the line 3—3, Figure 2;

Figure 4 is a transverse vertical section as indicated by the line 4—4, Figure 1;

Figure 5 is a detail in side elevation of a modified gearing;

Figure 6 is a section on line 6—6, Figure 5;

Figure 7 is a sectional plan view showing a modification of the manner of forming the racks on the sashes.

Referring at first more particularly to Figures 1 to 4, the numeral 10 designates

generally a window formed in a cement wall for example. 11 indicates the inner and outer sashes and 12 indicates sheet metal window jamb strips applied to the main jambs of the window and here shown as of angle shape in cross section. The strips 12 may be suitably anchored in place as at 13.

In lateral recesses of the window frame 10 adjacent the level of the meeting rails of the sashes 11 are provided gear boxes designated generally by the numeral 14 in which are U-shaped frame elements 15 that may be secured as by screws 14^a to each box or casting 14. The frame members 15 have spaced sides and are disposed vertically in the plane of the window so that the open sides of said elements 15 of the opposite jambs are disposed toward each other.

The free edges of the sides of the frame elements 15 are secured to flanged vertical U-shaped jamb strips 16 as by screws 17. The numeral 18 indicates Z-shaped stops disposed against the flanges of jamb strips 16, outside of the sashes 11, and 19 indicates the parting strips applied to the faces of the jamb facings 16.

Turning in the sides of each frame 15 are upper and lower shafts 22 the one shaft extending at one end beyond said frame and the other shaft 22 extending at its opposite end beyond said frame 15. The extending ends of the shafts 22 have pinions 23 fixed thereon and on said shafts within each frame 15 are intermeshing idler pinions 24, thereby gearing up one shaft 22 with the other so that the one shaft will respond to the turning movement of the other. The inner sash 11 has a rack 25 meshing with one pinion 23 and the outer sash 11 has a similar rack 25 meshing with the other of said pinions 23. The racks 25 are formed on side members 26 of the sashes 11, said side members being of channel form, the outer leg of the channel being accommodated between the adjacent side of the jamb strip 16 and the adjacent Z-shaped stop 18. In the form shown in Figures 1 to 3, the channel side members 26 of the sash are reinforced at the 100 rack teeth thereof by applied strips 25^a to give the rack teeth the required width for effective engagement with the pinion 23.

With the described arrangement it will be

seen that any movement of one sash 11 will be communicated through the engaged pinion 23, shafts 22, intermeshing idler pinions 24, the opposite pinion 23, to the rack 25 of the other sash.

The arrangement is such that the sashes will be constrained to move in parallel planes and prevented from tilting and binding against the guiding surfaces.

10 In Figures 5 and 6 the parts are the same as described and need not be specially referred to except the gearing which in Figures 5 and 6 includes pinions 23^a meshing with the rack teeth 25 of the channel members 26 of the sashes 11. Said pinions 23^a are fast on shafts 22^a turning in the boxing 14^b and side frame members 15^a in said boxing between which is a U-shaped frame member 15^b secured to the members 15^a by screws 30. On the shafts 22^a also are beveled pinions 24^a with which meshes an intermediate beveled pinion 24^b on a stud shaft 24^c turning in the frame member 15^b and in a reinforce bar 15^e applied to said 26 U-shaped member 15^b.

30 In Figure 7 the gearing is adapted to a wooden sash 11^b and a wood window frame 10^b for which purpose the sashes have vertical channels 11^c in the side edges in which channels are fitted rack bars 25^c engaging the pinions 23^b. The boxing 14 previously described has secured thereto the U-shaped frame element 15 by a screw 14^d as in Figure 1. The pinions 23^b are on shafts 22^b turning in the frame 15 and in the boxing 14. With this form of the invention intermeshing idler pinions 24^c on the respective shafts 22^b are employed substantially as in the first-described construction.

40 I would state in conclusion that while the illustrated examples constitute practical embodiments of my invention, I do not limit myself strictly to the exact details herein illustrated, since manifestly, the same can be 45 considerably varied without departure from

the spirit of the invention as defined in the appended claims.

Having thus described my invention, I claim:

1. In a window, a window frame having vertical jamb elements, stops outside of said jamb elements, sliding sashes, channel side members on said sashes, each channel member having a longer and a shorter leg, the longer legs extending between said jamb elements and said stops and formed with racks, the shorter legs of the channel members having their edges adjacent to the faces of said jamb elements, pinions meshing with said racks, and means to constrain the pinions to turn in unison in opposite directions.

2. In a window, a window frame having vertical jamb elements, stops outside of said jamb elements, sliding sashes, channel side members on said sashes, each channel member having a longer and a shorter leg, the longer leg extending between said jamb elements and said stops and formed with racks, reinforce strips on said longer legs at said racks, shafts, pinions fixed on said shafts and meshing with said racks, and means to constrain the pinions to turn in unison in opposite directions.

3. In a window, a window frame having vertical jamb elements, stops outside of said jamb elements, sliding sashes, channel side members on said sashes, said side members having short legs disposed against the faces of the jamb elements and having longer legs extending laterally outward into a plane at a side of the jamb elements, the edges of said offset portions of the channel members being formed with racks, shafts, pinions fixed on said shaft and meshing with said racks, and means to constrain said pinions to turn in unison in opposite directions.

LOUIS LANE.
